C. A. PSILANDER,
UNIVERSAL SPRING BOX,
APPLICATION FILED MAY 1, 1920.

1,409,775.

Patented Mar. 14, 1922.

UNITED STATES PATENT OFFICE.

CHARLES A. PSILANDER, OF EASTON, PENNSYLVANIA, ASSIGNOR TO WILLIAM WHARTON, JR. & COMPANY, INCORPORATED, OF EASTON, PENNSYLVANIA, A CORPORATION OF PENNSYLVANIA.

UNIVERSAL SPRING BOX.

1,409,775.

Specification of Letters Patent. Patented Mar. 14, 1922.

Application filed May 1, 1920. Serial No. 378,130.

To all whom it may concern:

Be it known that I, CHARLES A. PSILANDER, a citizen of the United States, residing at Easton, in the county of Northampton 5 and State of Pennsylvania, have invented certain new and useful Improvements in Universal Spring Boxes, of which the following is a specification.

This invention relates to an improvement 10 in spring boxes for operating switch tongues, wherein provision is made for yieldingly maintaining the switch tongue in either one of its two opposed positions, and insuring its return to such position 15 when displaced; or wherein the switch tongue may be yieldingly locked in any one particular position to which it may be moved through any agency.

The improved switch spring box is provided 20 with a member, which through a simple adjustment, may by the co-operation of spring arms yieldingly hold the switch tongue in either of its two positions, or lock such tongue by such spring pressure in 25 either position to which it may be moved. Under the first adjustment, the switch tongue, set for example to maintain an open straight track, will yield under displacement by the car wheels entering from the 30 curve, but will automatically return to its initial position following such displacement. Under the other adjustment of the member, the switch tongue when initially displaced 35 from its set position, will be yieldingly locked in the new position until again displaced.

A particularly important feature of the present invention, is the provision of automatic means, such, for example, as a dash 40 pot, wherein the movement of the switch tongue under the mechanism of the spring box, will be retarded in the final portion of its movement, to thereby prevent jar of the parts in operation, and also to prevent 45 splashing of any water that may have collected in the switch tongue recess.

The invention will be described in the following specification, reference being had to the accompanying drawings, in which:— 50 Fig. 1 is a plan of the improved spring box in applied position, the cover plate being removed, and the spool set for the automatic return control of the switch tongue.

Fig. 2 is a vertical sectional view of the same.

Fig. 3 is a transverse section on the line 3—3 of Fig. 1.

The improved spring box comprises a box-like casing, having an open end to abut the switch body 2, and secured to the latter, 60 as by bolts 3. The switch body has the usual switch tongue 4, working in the tongue recess 5, and having a lug 6, depending in a channel transverse the switch body and in line with the box 1.

The box proper is of less height than the thickness of the switch body, the end of the box remote from the switch body being appropriately supported, as at 7. The bottom of the box is imperforate, and provided 70 at about its midlength with a rounded projection, forming a bearing 8, and mounted in such bearing 8, is a spool 9.

The spool constitutes the adjusting element for changing the box from an ordinary spring box to a lock box at will, 75 and for this purpose, such spool is formed at diametrically opposite points with V-shaped depressions 10, and further formed in a diametric line at right angles to the 80 depressions 10, with V-shaped extensions 11. The spool is rotatable in the bearing 8, to bring either the depressions 10 or extensions 11 into operative positions, and through this adjustment the type of spring 85 box is changed as stated.

The spool is connected with the switch tongue 4, by means of an adjustable connection comprising a pipe section 12, held in the tongue lug 6, by nuts 13, and a rod 90 14, threaded into an axial opening 15 in the spool, lock nuts 16 completing the connection. The tongue may be readily adjusted with regard to its distance from the spool, both to obtain accurate operation, 95 and to set the parts so that as an ordinary spring box, the tongue may be yieldingly held in either of its two positions, as desired.

Pillars 17 formed as a part of the box and 100 arranged in rear of and beyond the spool, pivotally support bearing arms 19 by means of pins 18, the forward ends of which are formed or provided with V-shaped projections 20, adapted to more or less accurately 105 fit the depressions 10 or co-operate with

the extensions 11 of the spool. Flat leaf springs 21, of appropriate strength are secured at their forward ends to the box structure, and overlie and bear at their rear ends on the arms 19, being slidably connected to such arms at such bearing points, and exerting tension on the arms at all times.

The construction so far described is complete for the tongue operating function, it being apparent that with the spool turned to arrange the depressions 10 to receive the projections 20 of the arms, and the connection between the spool and switch tongue adjusted for length to set the tongue for the straight track for example, the displacement of the tongue by a car wheel entering from the curve, will move the spool against the tension of the springs 21, the inclined sides of the arm projections 20 riding but not moving beyond the ends of the inclined sides of the spool depressions 10. When the displacing pressure on the switch tongue is relieved, the springs 21 will return the spool and with it the switch tongue, to original position. Obviously, the connection between the switch tongue and spool may be adjusted to arrange the set position of the switch for the curve track, whereupon a train passing the switch on the straight track, will displace the tongue, with exactly the result described above, the tongue returning to the curve track set position when the displacement pressure is released.

If, however, the spool is turned through ninety degrees, the spool extensions 11 are engaged by the arm projections 20, and in the movement of the switch tongue, and therefore the spool, the arm projections 20 will override the spool extensions 11, that is, moved beyond the vertices of the said extensions, and thus hold the spool and thereby the switch tongue in either position according to its last displacement.

An important feature of the present invention resides in the provision of means, here shown as a dash-pot, for retarding the final movement of the switch tongue in either direction under the influence of the spring action.

The dash-pot retarder comprises a casing 22, arranged within the box in line with the spool 9, and having a cylindrical bore therein as at 23. A piston 24 operates in the bore or cylinder, the rod 25 of which extends through a suitably packed opening in the casing 22 and is adjustably connected to the spool, as by a threaded union 26. The piston fits the cylinder with sufficient accuracy to prevent other than a comparatively slow leakage around the edge of said piston of the material or fluid ahead of it in the bore, as is usual in dash-pot construction. Below the cylinder the casing is formed as a chamber 27, having openings 28, leading into the cylinder at the respective ends there-

of, upwardly acting ball valves 29, normally closing said openings 28. The chamber 27 communicates with the cylinder at mid length of the latter, as at 30, so that the chamber acts to transfer fluid from one side of the piston to the other in moving past the opening 30. The casing 22 has a cover plate 31 to be secured thereto in a fluid tight manner, and formed with a filling opening 32, through which oil or similar fluid may be supplied to fill the casing. The adjustment of the connection between the dash-pot piston and the spool 9 should be such that the piston is midlength the cylinder of the dash-pot when the switch tongue is at half-throw. Thus on completion of the switch tongue movement in either direction, the movement of the piston is retarded by the oil ahead of it in the cylinder, to thus retard the completion of the switch tongue throw, as and for the purposes stated.

The valve controlled openings 28 serve to overcome the vacuum producing tendency of the piston in moving from a particular end of the cylinder, as in the commencement of the switch tongue movement.

The box 1 has a cover plate 33 designed to be secured thereto in a fluid tight manner, in order that the box 1 may be filled with oil, if desired and as preferred, to retard wear and prevent rust of the parts.

Having thus described the invention, what is claimed as new is:—

1. A switch tongue spring box having a rotatable spool connected to and movable with the switch tongue, and spring means exteriorly bearing on the spool, the rotation of the spool changing the effect of the spring means thereon.

2. A spring box having a spool connected to the switch tongue, said spool having depressions and extensions, spring means for cooperating with the spool, the spool being rotatable to cause the spring means to cooperate with either the depressions or extensions.

3. A switch tongue spring box having a rotatable spool formed with depressions and with extensions, arms formed to cooperate with either the depressions or extensions, and flat springs exteriorly bearing on said arms, whereby through the rotation of the spool the arms may be caused to cooperate with either the depressions or extensions of the spool.

4. A switch tongue spring box, including flat spring strips, and a spool connected to the tongue and formed to be influenced by said spring strips, said spool being rotatable to vary the effect of the spring-strip influence thereon.

5. A switch tongue spring box, including a spool mounted for rotation and adjustably connected to the tongue, arms pivotally mounted in the box and formed to cooperate

with the spool, and flat springs secured in the box and bearing on the arms, said spool being formed at distinct points with non-similar formations, either of which may be 5 brought into cooperation with said arms.

6. A switch tongue spring box having a spool connected to and movable with the tongue, and spring members cooperating with the spool to control the tongue, the 10 spool being adjustable to vary the effect of the spring members thereon.

7. A switch tongue spring box having a rotatable spool connected to and movable with the tongue, and spring members to 15 cooperate with said spool for controlling the movement of the tongue, the spool being adjustable to alter the final influence of the spring members with respect to the spool.

8. A switch tongue spring box having a 20 spool connected to and movable with the switch tongue, and spring members to cooperate with the spool, said spool being adjustable with respect to the tongue and

formed to cooperate with the spring members for distinctly different results under 25 different adjustments of the spool.

9. A spring box having a spool connected to and movable with the switch tongue, and spring members exerting an endwise influence on the spool following movement thereof of the spool being adjustable with respect to the tongue to vary the effect of the endwise influence of the spring members on the spool at will. 30

10. A spring box having a spool connected to and movable with the switch tongue, said spool being adjustable with respect to the tongue, and spring members cooperating with and adapted to influence movement of the spool, said spring members continuing 40 a predetermined spool movement under one adjustment of the spool and compelling a return spool movement under another adjustment of the spool. 35

In testimony whereof I affix my signature. 45
CHARLES A. PSILANDER.
